UNITED STATES PATENT OFFICE.

HENRY WATKEYS, OF SYRACUSE, NEW YORK.

BREECH-LOADING FIRE-ARM.

SPECIFICATION forming part of Letters Patent No. 246,052, dated August 23, 1881.

Application filed September 25, 1880. (No model.)

To all whom it may concern:

Be it known that I, HENRY WATKEYS, of Syracuse, in the county of Onondaga, in the State of New York, have invented new and useful Improvements in Breech-Loading Fire-Arms, of which the following, taken in connection with the accompanying drawings, is a full, clear, and exact description.

This invention relates to simple, safe, durable, and effective means of locking a hinged barrel in its operative position on the stock, as hereinafter fully described, and specifically set forth in the claims.

In the accompanying drawings, Figures 1 and 2 are longitudinal sections of a breech-loading gun provided with my improvements, and showing the relative position and action of the respective elements of the invention. Fig. 3 is a transverse section on line $x-x$ in Fig. 2; Fig. 4, a transverse section on line $y-y$ in Fig. 2; Fig. 5, a rear-end view of the barrel. Figs. 6, 7, and 8 are a plan view, inverted view, and side view, respectively, of the extractor. Figs. 9 and 10 are detached side and bottom views, respectively, of the plug or bolt by which the barrel is locked in its operative position. Figs. 11 and 12 are front and rear end views, respectively, of the aforesaid plug or bolt; and Fig. 13 is an enlarged longitudinal section of my invention, illustrating certain modifications in its construction.

Similar letters of reference indicate corresponding parts.

A denotes the stock of the gun, having the forward extension, C, usually termed "breech-extension," to the extremity of which is hinged the barrel B, said hinged connection consisting of a segmental shoulder, m, formed in the mortise K of the breech-extension C, and a lug, h, on the under side of the barrel, having a corresponding segmental recess, i, bearing on the shoulder m. Back of the described hinge are two hooks, D and E, formed, respectively, by a rigid downward and forward projection on the under side of the barrel, and a rigid bridge with a rearward projection in the usual mortise, K, in the breech-extension C, said hooks interlocking when the barrel is tilted, as shown in Fig. 1 of the drawings, and forming a simple, reliable, and durable means for limiting the said motion of the barrel. The stock is provided with a cylindrical chamber,

d, directly back of and in line with the barrel. In said chamber is fitted to slide a cylindrical plug, a, having its forward end fitted to the rear end of the barrel by an annular concavo-convex joint, as best seen in Fig. 13 of the drawings, so as to effectually close the bore and at the same time confine the barrel in its normal or operative position on the stock. The described concavo-convex joint of the plug and barrel allows for the wear of the hinge-connection of the barrel and stock and the wear of the mechanism actuating the plug, so that in case the said parts fail to operate in exact unison with each other the barrel cannot become bound on the end of the plug, which would be the case were the aforesaid joint made conical or with a uniform bevel.

The plug a is moved longitudinally and caused to either engage or release the barrel by means of a lever, L, pivoted to the stock, and having an arm, l, entering a mortise, v, in the plug. A tapered or wedge-shaped tongue, c, hinged to the lever L, back of the fulcrum thereof, is forced between the rear end of the plug and the adjacent end of the chamber d by means of said lever, when operated to move the plug forward to engage the rear end of the barrel, said tongue serving as a backing to resist the rebound of the plug a when the gun is discharged. Automatically with the reverse movement of the lever L, and the consequent rearward movement of the plug a, the tongue c is withdrawn from behind the plug. The mortise v in the plug is of such length as to allow the arm l to play therein without disturbing the plug until the tongue c is sufficiently withdrawn to admit of the movement of the plug. The wear and abrasion of the tongue c, and that of the surfaces adjacent thereto, is compensated by a liner or gib, e, applied to either the end of the plug, as shown in Figs. 1 and 2 of the drawings, or to the end face of the chamber d, as illustrated in Fig. 13 of the drawings.

g denotes the firing-pin passing through a channel, f, extended longitudinally through the plug a, and in proper position to receive the stroke of the hammer at its rear end and strike with its forward extremity the priming of the cartridge or shell.

n represents the extractor, having its rear end of the usual form, adapted to engage the

- peripheral flange at the rear end of the cartridge or shell. The extractor has a forward-extended bar, n' , by which it slides longitudinally in a channel, o , formed in a downward projection on the under side of the barrel B . A link or rod, r , is connected at one end directly to the extractor-bar, and at the opposite end to a fixed point in the stock back of the breech. This direct connection of the link r with the extractor, and the relative position of the connections of said link, throws the latter into such an angle by the tilting of the barrel as to cause the link to not only draw the extractor rearward, but also push the same forward automatically with the tilting of the barrel, as shown in Figs. 1 and 2 of the drawings.
- I am aware of the prior use of the link r in combination with an extra sliding block for forcing the extractor rearward, and a spiral spring for drawing the extractor forward; but the device which I have herein described and shown in the drawings differs from such a contrivance in that it dispenses with both the extra sliding block and the spiral spring, thus materially simplifying and cheapening the construction, and at the same time rendering the action of the extractor more positive and durable.
- To further simplify the construction and dispense with the employment of an extra pin for the connection of the rear end of the link

r , I make said connection with the pin s , by which the lever L is pivoted to the stock, but in no wise allow the action of said lever to affect the link r . 35

I am aware that it is not new to lock a hinged barrel in its operative position on the stock by means of a plug entering the breech of the barrel, and therefore do not claim, broadly, such a device; but 40

What I do claim as my improvements are—

1. In combination with the hinged barrel B , the stock A , provided with the chamber d , the sliding plug a , provided with the elongated 45 mortise v , the lever L , having the arm l , playing in the mortise v , and the tongue c , hinged to the lever L , and sliding between the rear end of the plug and end of chamber d , all arranged and operating substantially in the manner shown and set forth. 50

2. The combination, with the stock A , sliding plug a , and tongue c , of the liner or gib e , substantially as and for the purpose set forth.

In testimony whereof I have hereunto signed 55 my name and affixed my seal, in the presence of two attesting witnesses, at Syracuse, in the county of Onondaga and State of New York, this 23d day of August, 1880.

HENRY WATKEYS. [L. S.]
